CLAIM

The ornamental design for a faucet, as shown.

DESCRIPTION

FIG. 1 is a perspective view taken from the top, front and right side of a faucet showing my new design;

FIG. 2 is a front elevational view thereof;

FIG. 3 is a rear elevational view thereof;

FIG. 4 is a left side elevational view thereof;

FIG. 5 is a perspective view taken from the top, front and right side of a modified form of the faucet shown in FIG. 1;

FIG. 6 is a front elevational view of FIG. 5;

FIG. 7 is a rear elevational view of FIG. 5; and

FIG. 8 is a left side elevational view of FIG. 5.
